UNITED STATES PATENT OFFICE.

FRANCIS I. HOEFLER, OF CINCINNATI, OHIO, ASSIGNOR TO THE CINCINNATI COFFIN COMPANY, OF CINCINNATI, OHIO, A CORPORATION OF OHIO.

CASKET-FASTENER.

SPECIFICATION forming part of Letters Patent No. 729,865, dated June 2, 1903.

Application filed March 26, 1900. Serial No. 10,189. (No model.)

To all whom it may concern:

Be it known that I, FRANCIS I. HOEFLER, a citizen of the United States, and a resident of the city of Cincinnati, in the county of Hamilton and State of Ohio, have invented certain new and useful Improvements in Devices for Fasteners for Securing Lids to the Bodies of Interior Linings of Caskets and other Boxes, of which the following is a specification.

10 My invention is primarily designed for use in connection with what is known as the "metal interior lining of caskets." These metal interior linings consist of a receptacle and a separable lid, together making a complete box. The receptacle is located within the burial-casket and the lid duly fastened thereon, and then the casket-lid is fastened down over the first-named lid and the casket is complete. In practice the metallic interior lining being within the casket, the corpse is duly placed therein, and the lid of this lining is placed upon a rubber gasket located upon the upper edge of the wall of the lining, and then the lid is forcibly pressed toward the wall of the lining, thus compressing the gasket and rendering the joint there air-tight.

15 The principal object of my invention is to provide simple and economical means for holding the lid of the lining down upon and close to the edges of the walls of the same. These means are easily manipulated, very effective in operation, and durable.

20 The several features of my invention and the various advantages resulting from their use conjointly or otherwise will be apparent from the following description and claims.

25 Inasmuch as a description of the application of my invention to the box-lining of a casket will sufficiently illustrate its nature, I have in the drawings shown such a box-lining and the application to it of my improved fastener.

30 In the accompanying drawings, making a part of this application, and in which similar letters indicate corresponding parts, Figure 1 is an elevation, partly in section and partly in elevation, of a casket interior lining and my invention applied thereto. A key for operating the locking device is shown in elevation at the upper part of the figure. Fig. 2 is a view in perspective of my locking device

and showing in dotted lines a part of the casket interior lining and rubber gasket as combined with my device. Fig. 3 presents a view in perspective of an end portion of the casket 55 interior lining and a series of my locking devices applied thereto.

I will now proceed to describe my invention in detail.

A indicates the metal interior lining as an 60 entirety. Such receptacle may be of any suitable conformation adapted in shape to fit the interior of the casket with which it is to be used.

B indicates the lid, C the side and end walls, 65 and C² the bottom of the lining.

Upon the upper edge of the wall C there is laid or fastened a rubber gasket D, adapted to receive the edge portion of the lid B.

Upon the top of the wall C and so as to 70 stand just outside of the lid are located a suitable number of devices, each made according to my invention and as follows: The device has a base E, adapted to be secured to the wall—for example, the base E has two 75 holes E² E² each for receiving a screw E³ to be screwed into the wall C. The lining A is usually made of zinc or other thin metal, and in such event the upper edge of the wall is constructed so as to present a surface sufficiently broad to receive the base E of the device and also the rubber gasket, upon which the lid is to rest. The preferred construction for this purpose consists in locating a strip C², usually of wood, as shown, and holding it in place by bending the upper edge portion of the wall C over the top down against the inner side and then under and against the bottom of it. In such construction the wall is originally left higher than it is to actually be in order to allow for the amount thus taken up in bending it around the strip C², as described. Each of the screws E³ passes through the metal of the wall at top of the strip and then down into the strip, substantially as shown.

From the base E of the device aforementioned rises a hollow standard H, provided with two extension-flanges H² and H². Between these is a narrow space H³, which extends back to that hollow space of the standard which receives a shaft K. In this space

H^3 is located the rotatable shaft K. The shaft near its lower end is diminished in size, forming a contracted portion K³. This contracted portion is passed into and extends 5 through the neck or smaller portion of a beveled opening E⁴ of the base-plate E. That part of the shaft below this neck enlarges, so as to fill the remainder of this opening E⁴, which enlarges, as heretofore mentioned, and 10 as shown. This enlargement of the shaft in the lower portion of the opening E⁴ is accomplished, preferably, by an operation substantially similar to that of riveting the head of a bolt or spreading the end of a rivet-rod. 15 This enlargement of the lower end of the part K³ becomes the enlargement K². The shaft K is thus firmly held to the base-plate E. The particular manner of making this enlargement by spreading the stem is not essential 20 to this invention. The essential features of the connection are that the shaft K be rotatable relatively to the base-plate. It is obviously desirable that the connection to the base-plate be such as shall not extend below 25 the latter. The shank K, at its upper end, and at the upper end of the standard, has an enlarged head K⁴, which extends over the top of the standard H and may be said to rotate thereon. Such head K⁴ prevents the vertical 30 shank from slipping down out of place. This head K⁴ is adapted to be engaged by a suitable key, whereby it and its shank can be rotated. The mode of engagement between the key and the head may be varied. One 35 of the preferred modes is that shown, and consists in providing the head with a vertical slot M, having at its bottom a recess M². The key N to engage such slot and recess, besides having a handle of suitable form, has 40 a flat portion N² and a terminal pin or small extension N³. The flat portion N² fits within the slot, while the pin N³ fits into the recess M². When thus engaged, the key when rotated will rotate the shank K. The shank 45 has a screw or spiral flange K⁵ upon it. Within the space H³ is located a jaw P, arranged to oscillate on a pivot P². The front or free end P³ of the jaw P extends out beyond the flanges H² H², as shown, and the 50 rear end has a circular portion P⁴, provided with ratchet-teeth P⁵, two or more of which latter at all times engage with the screw or spiral K⁵. As the shank K by the key is rotated in one direction the spiral K⁵ elevates 55 the rear end P⁴ of the jaw, and thus depresses the front end. The latter when the lid is in place as a part of the lining engages the edge B² of the lid B and forces the latter down hard upon the gasket D, and thus not only 60 holds the lid in position, but hermetically seals the joint between the lid and the wall C. It will be understood that the edge B² of the lid B is preferably stiff, and to this end consists of a stiff bar of metal suitably 65 cured to the otherwise thin metal of the lid. This lid is usually provided near one end with an opening filled by a glass plate her-

metically sealed in and to the lid. When the lid is to be removed, the shank is duly rotated in a reverse direction, thus depressing the rear end P⁴ of the jaw and elevating the front end P³ of it. This front end can be and is elevated until it comes entirely within the space H³ between the flanges H². Dotted lines in Fig. 2 show this elevated position of the jaw. When thus placed, it is out of intervention and leaves the way free for the lid to be elevated and withdrawn from the rest of the casket. For the same reason the lid can be readily placed upon the wall C. 80 Thereupon the jaw can be advanced and depressed and made to engage the lid, as heretofore specified.

It is to be noted that the series of these devices arranged upon the upper edge of the 85 wall around the lower portion of the receptacle constitute a very efficient set of guides, within which the lid can be placed, as shown, and also a very efficient set of stops which prevent the lid from slipping laterally out of 90 place. It is also to be observed that this series of such clamping devices enables the lid, gasket, and wall to be everywhere tightly 95 compressed together. For example, should there be slightly uneven places in these parts these devices will at close intervals efficiently compress the parts at and in their vicinity, and thus the lid will be sealed to the wall for their entire length.

It is to be understood that while this invention is primarily designed for use in connection with the interior lining of caskets it is not to be confined thereto. I claim its application for clamping down the lids of other boxes and for obvious uses. 100 105

What I claim as new and of my invention, and desire to secure by Letters Patent, is—

1. As a device for holding a lid upon a box, the combination of the base E, standard H, shaft K, having a screw-thread and located 110 in the standard, held therein but rotatable, head K⁴, adapted to engage with a key for rotating the shaft, flanges H², H², between which is space H³, jaw P within such flanges, and pivoted at P², one end of the jaw engaging a 115 spiral on the shaft K, and the other end adapted to engage the lid, when the shaft is rotated in one direction, and adapted to be elevated so as to have its bottom flush with the front edges of the flanges H², when the shaft is rotated in the other direction, substantially as 120 and for the purposes specified.

2. In combination with a lid and the receptacle it covers, a device having a base adapted to be secured to the upper wall of the receptacle, a standard rising therefrom and provided with extensions, the standard having a vertical space and there being a space between the extensions, leading into the vertical space, on the one edge and opening outward on the other, a screw-threaded shaft occupying the vertical space of the standard, and having above a head bearing on the standard, and adapted to be rotated and below 125 130

passing through an opening in the base into an enlarged recess and there enlarged, an oscillating jaw located in the space between the extensions, and pivoted thereto, the rear end 5 of the jaw adapted to engage the screw-thread of the shaft, and the free end to move out from the extensions and hold together the lid and receptacle, and also adapted to be moved out of the way, and back, substantially as c and for the purposes specified.

3. The combination of a sheet-metal coffin-body having the strip C², and the metal C bent upon the top and the inner edge, and onto the bottom of the strip and forming a 15 support for the coffin-lid and the fastening device, a lid having the edge B², extended out toward the fastening device, a gasket D, located between the edge B² and the support C, C², and the metal base E secured to this 20 support C, C², and the hollow standard H

arising from this base, and having the passage-way E⁴, and the flanged parallel extensions H², H², extending forward toward the coffin-lid, jaw P, pivoted at P² to the flanged portions H², and carrying a circular toothed 25 portion P⁴, P⁵, and a shank or shaft K, having a screw-thread engaging the toothed portion P⁴, P⁵, the shank K having the contracted portion or neck K³, located in the upper part of passage E⁴, and a basal enlargement 30 K² of the shank located below the neck K³, and adapted to secure the rotatable shank in place, the extension H² and standard H and base E being integral, substantially as and for the purposes specified.

FRANCIS I. HOEFILE.
